SYLVANIA, A CORPORATION OF PENNSYLVANIA

TUBE FRAME

Application filed February 24, 1932. Serial No. 594,764.

This invention relates to improvements in yarn spool carriers or tube frames for use in looms for weaving tufted pile fabrics such as Axminster carpets and rugs.

5 In the manufacture of wide, seamless rugs, spool carriers or tube frames are employed in which each carrier or frame is provided with a plurality of co-axially alined yarn spools which are rotatably supported by bearing brackets on the frame bar thereof.

The object of the invention is to provide a novel, simple and advantageous means for rotatably supporting and connecting the adjacent ends of yarn spools, first, whereby the 15 connected spools will be caused to rotate in unison; second, whereby the spools may be easily and quickly applied to and removed from the supporting and connecting means; third, whereby the ends of the intermediate 20 spools may be reversed or substituted one for the other when more than two spools are carried by a frame; and, fourth, whereby various novel and desirable results are attained.

The invention resides in the elements and 25 the combinations of them hereinafter described and claimed.

In the accompanying drawing, illustrating the invention,

Figure 1 is a front view of a yarn spool 30 carrier or tube frame, showing one form of embodiment of the invention, certain parts between the ends thereof being broken away, and certain parts being shown in section.

Figure 2 is a transverse section thereof, on 35 line 2—2 of Fig. 1.

Figure 3 is a detail, showing one of the intermediate bearing brackets in the open position.

Figure 4 is a vertical section through one of 40 the intermediate bearing brackets and a part of the frame bar.

Figure 5 is a detail, showing one of the intermediate bearing brackets with the rotatable spool connecting member removed therefrom.

Figure 6 is a front view of one of the rotatable spool connecting members removed from its bearing bracket.

Figure 7 is a side view thereof.

50 Referring to the drawing, 3 designates the

long frame or body bar of the tube frame or spool carrier. The respective ends of the bar 3 are provided with oppositely disposed chain engaging brackets 4 and latch arms 5 for connecting the frame or carrier to the chains of 55 the loom which carry the frames successively into the operative position with respect to the weaving instrumentalities of the loom, in the usual, well-known manner.

The frame bar 3 is provided with the usual 60 tubes 6 or equivalent guiding devices through which the tuft yarn ends extending from the yarn spools 7 are drawn and guided during the weaving operation.

When two or more yarn spools 7 are carried 65 by the frame or carrier, the spools extend in axial alinement, parallel to the frame bar 3, and the outer ends of the outermost spools are provided with axially projecting pins 8 forming journals which extend into bearing 70 openings in bearing brackets or arms 9 which are secured to the brackets 4 and are fixedly related to the frame bar 3.

Each journal or pin 8 is slidable longitudinally in sleeve or bushing 10 which is 75 fixed in the adjacent end of the spool, and the pin 8 is urged outwardly by a spring 11 which is located within the sleeve 10 and within a bore in the enlarged inner end portion of the sleeve, as shown in Fig. 1. Outward movement of the pin 8 is limited by the outer end of the enlarged inner end portion of the pin engaging an inwardly extending flange on the outer end of the sleeve. The pin 8 is provided with a collar 12 which is 80 adapted to engage the bracket 9 and yielding- 85 prevent outward axial displacement of the spool. The spring 11 also permits the pin 8 to yield inwardly during the applica- 90 tion of the spool to its bearings.

Mounted on the frame bar 3, between the end spool bearing brackets 9, in spaced relation thereto and to each other, are intermediate spool bearing brackets 17 which correspond in number with the pairs of adjacent 95 and opposing ends of the spools 7 making up the series thereof carried by the frame. Thus it will be understood that a frame carrying two spools would be provided with one intermediate bearing bracket 17, a frame carrying 100

three spools would be provided with two intermediate bearing brackets, and so on, an intermediate bracket being added for each additional spool.

- 5 Each spool end adjacent to an intermediate bearing bracket 17 is provided with an axial journal member comprising a body part 19 of cylindrical or other suitable form secured within the spool, and a flat, plate-like journal part 20 projecting from the body part 19 co-axially with the spool and extending transversely of the spool axis on the respective sides thereof.
- 10

The intermediate bearing brackets 17 are 15 alike in construction and each includes a body portion 21 having a base flange 22 secured to the frame bar 3, and a movable element 23 fitted against one side of the body 21 and held normally in its operative position in parallel contact therewith by a spring 24 which encircles a screw 25. The screw 25 projects fixedly from the body portion 21 and through an opening in the element 23, and the spring 24 acts between a head on the screw 25 and the element 23 and urges the latter toward its normal or operative position, as shown in Figs. 2, 4 and 5, and against the yielding action of which the upper portion of the element 23 may be moved outwardly from the body portion 21, as shown in Fig. 3, for a purpose hereinafter explained.

An annular bearing opening 26 is formed by and between the upper portions of the body portion 21 and element 23 of the bracket 17, and a connecting member 27 is rotatably supported within the opening 26 co-axially with the spools 7. The connecting member 27 comprises a cylindrical body provided with outwardly extending flanges 29 on the respective ends thereof which are fitted to rotate in annular grooves 30 formed in the respective sides of the body portion 21 and the element 23 of the bracket. These flanges 29 serve to prevent axial displacement of the members 27 within the brackets 17, and the outer surfaces of the flanges are confined within the grooves 30 so that they will not present obstructions interfering with the easy insertion of the spools 7 between the bearing brackets of the tube frame.

50 Lateral displacement of the element 23 with respect to the body portion 21, in directions longitudinally of the spools or frame, is prevented by the flanges 29, the screw 25 and a pin 31 projecting fixedly from the body portion 21 and into a slot or cavity in the element 23.

The respective end portions of the connecting member 27 are provided with transversely extending grooves 32 which cross the axis of the member. The grooves in one end portion of the member 27 are out of line with or set at angles with relation to the grooves in the other end portion thereof so that the grooves 65 can extend to or pass the center of the mem-

ber 27 without splitting the same. These grooves 32 are adapted to receive the plate-like journal parts 20 of the spools 7 and the width of each part 20 is equal or substantially equal to the diameter of the cylindrical body 70 of the member 27 and the diameter of the bearing opening 26.

When the connecting member 27 of one of the brackets 17 has the journal parts 20 of the adjacent ends of two spools 7 inserted into 75 the grooves 32 in the respective end portions thereof, as shown in Figs. 1 and 2, the annular wall of the bearing opening 26 retains the parts 20 within the grooves 32 with their respective spools 7 in axial alinement, and the walls of the grooves cause the parts 20 and their spools to be rotated as a unit.

When it is desired to introduce the journal parts 20 to the grooves 32 of the connecting member 27, the upper end of the element 23 is moved outwardly against the action of the spring 24, as shown in Fig. 3, thereby opening a passage between the upper end portions of the element 23 and the body portion 21 through which the parts 20 may be moved 90 into and from the grooves 32 and the bearing opening 26 by transverse movement of the spools carrying the parts 20.

In order to facilitate the insertion of the journal parts 20 into the grooves 32 of the connecting member 27 and into the bearing opening 26, we provide the element 23 of the bearing bracket with an upwardly extending guide arm 33 provided with a guiding surface 34 for guiding the parts 20 into the bearing opening 26 and grooves 32 when the element 23 is moved to the position shown in Fig. 3. The arm 33 also serves as a means for permitting the element 23 to be easily moved to the open position, shown in Fig. 3, either by hand 105 or by the pressure of a journal part 20 against the arm 33 while a spool is being inserted into the bearing bracket of the frame.

The flanges 29 project from the respective ends of the member 27 between the outer ends 110 of the grooves 32 thereof, and the adjacent sides of the flanges 29 form outwardly flared entrance openings for guiding the journal parts 20 of the spools into the grooves 32.

It will now be understood that the spools 7 115 may be easily and quickly inserted into and removed from the connecting members 27 of the bearing brackets 17 by transverse movement of the spools, and that when the spools are applied to the tube frame, the connecting members 27 will cause equal rotation of the spools.

When the outer end of either outermost spool 7 is applied to the tube frame, the outer end of the journal pin 8 is inserted into the bearing opening in the bracket 9, the collar 12 engages the brackets and forces the pin 8 inwardly to some extent against the action of the spring 11, and, after the inner end of the spool is applied to one of the intermediate 130

bearing brackets 17, the spring 11 holds it in place therein.

Each end of the connecting member 27 is provided with two of the grooves 32 which cross one another at right angles, as illustrated, and the journal part 20 of the adjacent spool 7 may be inserted into either of the two grooves. The provision of the two grooves makes it unnecessary to turn the connecting member 27 more than a quarter revolution, at the most, to bring a groove 32 into registry with the passage between the upper end portions of the element 23 and body portion 21 when the part 20 is inserted into or removed from the bearing bracket.

An important feature of our invention resides in our novel construction which, not only provides for the equal rotation of the spools, but also permits the spools to be applied to and removed from the intermediate bearings of the tube frame by transverse movement of the spools, thereby enabling us to provide a sturdy and durable bearing structure within the limited space allowed between adjacent spool ends.

When more than two spools are employed in the tube frame, the ends of any intermediate spool may be reversed and connected to the same intermediate bearing brackets, and any intermediate spool may be substituted for any other and connected to the same intermediate bearing brackets. Also the outermost spools may be substituted for one another after first reversing the ends of each spool, and this may be done even though but two spools are employed in a tube frame having a single intermediate bearing bracket. These are important considerations in instances where the tuft yarns upon the spools bear particular relations to the pattern of the product of the loom, and where the tuft yarns upon the several spools cause the spools to bear particular relations to one another for the production of the pattern of the product. This is particularly true in avoiding the errors which have heretofore occurred in rolling or winding the pattern controlling yarns upon the spools with relation to the ends thereof in cases where the spools have not been reversible or interchangeable, as provided in our invention.

We claim:

1. In a tube frame, a frame bar, two coaxial spools having adjacent end portions and remote end portions, means on the bar for rotatably supporting the remote end portions of the spools, a bearing bracket carried by the bar for the adjacent end portions of the spools, a spool connecting member rotatably supported by the bracket and having transversely extending grooves in the respective end portions thereof, and transversely extending parts projecting from the adjacent end portions of the spools and into said grooves and adapted to engage the walls

thereof for causing equal rotation therewith, said parts being adapted to be inserted into and removed from said grooves by transverse movement of said spools.

2. In a tube frame, a frame bar, two coaxial spools having adjacent end portions and remote end portions, means on the bar for rotatably supporting the remote end portions of the spools, a bearing bracket carried by the bar for the adjacent end portions of the spools, a spool connecting member rotatably supported by the bracket and having transversely extending grooves in the respective end portions thereof, transversely extending parts projecting from the adjacent end portions of the spools and into said grooves and adapted to engage the walls thereof for causing equal rotation therewith, said parts being adapted to be inserted into and removed from said grooves by transverse movement of said spools, and means for retaining said parts within said grooves and operable to permit the same to be inserted into and removed therefrom.

3. In a tube frame, a frame bar, two coaxial spools having adjacent end portions and remote end portions, means on the bar for rotatably supporting the remote end portions of the spools, a bearing bracket carried by the bar for the adjacent end portions of the spools and having a bearing opening therein co-axial with the spools and having opposing walls extending outwardly from said opening and providing a passage, a spool connecting member rotatably mounted in said opening and having transversely extending grooves in the respective end portions thereof, and transversely extending parts projecting from the adjacent end portions of the spools and into said opening and said grooves and adapted to engage the walls thereof for causing equal rotation therewith, said parts being adapted to be moved through said passage into and from said grooves.

4. In a tube frame, a frame bar, two coaxial spools having adjacent end portions and remote end portions, means on the bar for rotatably supporting the remote end portions of the spools, a bearing bracket carried by the bar for the adjacent end portions of the spools and having a bearing opening therein co-axial with the spools and having opposing walls extending outwardly from said opening and providing a passage, a spool connecting member rotatably mounted in said opening and having transversely extending grooves in the respective end portions thereof, and transversely extending parts projecting from the adjacent end portions of the spools and into said opening and said grooves and adapted to engage the walls thereof for causing equal rotation therewith, said parts being adapted to be moved through said passage into and from said grooves, and

one of said walls being yieldable relatively to the other and movable therefrom to widen the passage between them for the accommodation of said parts.

5. In a tube frame, a frame bar, two coaxial spools having adjacent end portions and remote end portions, means on the bar for rotatably supporting the remote end portions of the spools, a bearing bracket for the adjacent end portions of the spools and comprising a body portion fixedly mounted on said bar and a movable element carried by the body portion and movable relatively thereto toward and from an operative position, a spool connecting member extending between and rotatably supported by said body portion and said element, parts projecting from the adjacent end portions of said spools and adapted to be moved between said body portion and said element into and from within said member and to engage parts thereof for equal rotation therewith when within the same, and means to hold said element in its operative position.

25 6. In a tube frame, a frame bar, two co-
axial spools having adjacent end portions
and remote end portions, means on the bar
for rotatably supporting the remote end por-
tions of the spools, a bearing bracket for the
30 adjacent end portions of the spools and com-
prising a body portion fixedly mounted on
said bar and a movable element carried by
the body portion and movable from and to-
ward an operative position in close proximity
35 thereto, a spool connecting member extending
between and rotatably supported by said
body portion and said element, parts project-
ing from the adjacent end portions of said
spools and adapted to be moved between
40 said body portion and said element into and
from within said member and to engage parts
thereof for equal rotation therewith when
within the same, and yieldable means op-
posing movement of said element from its
45 normal position.

7. In a tube frame, a frame bar, two coaxial spools having adjacent end portions and remote end portions, means on the bar for rotatably supporting the remote end portions of the spools, a bearing bracket for the adjacent end portion of the spools and comprising a body portion fixedly mounted on said bar and a movable element carried by the body portion and movable from and toward an operative position in close proximity thereto, a spool connecting member extending between and rotatably supported by said body portion and said element, parts projecting from the adjacent end portions of said spools and adapted to be moved between said body portion and said element into and from within said member and to engage parts thereof for equal rotation therewith when within the same, yieldable means opposing movement of said element from its normal

position, and a guide arm extending from said element and having a guiding surface for guiding said parts into positions between said element and said body portion.

8. A tube frame bearing bracket for the 70 adjacent ends of co-axial yarn spools, comprising a body portion adapted to be secured to a frame bar and having parts forming a bearing opening extending therethrough, and a spool connecting member extending 75 through and rotatably supported in said opening and having transverse grooves extending entirely across the respective end portions thereof located within said bearing opening for receiving complementary parts 80 of yarn spool journals.

9. A tube frame bearing bracket for the adjacent ends of co-axial yarn spools, comprising a body portion adapted to be secured to a frame bar and having parts forming a bearing opening extending therethrough, and a spool connecting member extending through and rotatably supported in said opening and having transverse grooves in the respective end portions thereof for receiving complementary parts of yarn spool journals, said grooves crossing the axis of the member, and a groove in one end portion thereof being set at an angle with respect to a groove in the other end portion thereof 85 90 95

10. A tube frame bearing bracket for the adjacent ends of co-axial yarn spools, comprising a body portion adapted to be secured to a frame bar and having parts forming a bearing opening extending therethrough, and a spool connecting member extending through and rotatably supported in said opening and having transverse grooves in the respective end portions thereof and extending within the respective end portions of said opening for receiving complementary parts of yarn spool journals within said grooves and within said opening.

11. A tube frame bearing bracket for the adjacent ends of co-axial yarn spools, comprising a body portion adapted to be secured to a frame bar, an element carried by the body portion and movable relatively thereto toward and from an operative position, and a spool connecting member extending between and rotatably supported by said body portion and said element when the latter is in its operative position, said member having transverse grooves in the respective end portions thereof and extending between said body portion and said element for receiving complementary parts of yarn spool journals, said element when moved from its operative position providing an opening between it and said body portion for the passage of said parts into and from said grooves, and means to hold said element in its operative position. 110 115 120 125

12. A tube frame bearing bracket for the adjacent ends of co-axial yarn spools, com- 130

prising a body portion adapted to be secured to a frame bar, an element carried by the body portion and movable relatively thereto toward and from an operative position, 5 and a spool connecting member extending between and rotatably supported by said body portion and said element when the latter is in its operative position, said member having transverse grooves in the respective end 10 portions thereof and extending between said body portion and said element for receiving complementary parts of yarn spool journals, said element when moved from its operative position providing an opening between it and 15 said body portion for the passage of said parts into and from said grooves, and yieldable means opposing movement of said element from its operative position.

13. A tube frame bearing bracket for the 20 adjacent ends of co-axial yarn spools, comprising a body portion adapted to be secured to a frame bar, an element carried by the body portion and movable relatively thereto toward and from an operative position, 25 and a spool connecting member extending between and rotatably supported by said body portion and said element when the latter is in its operative position, said member having transverse grooves in the respective 30 end portions thereof and extending between said body portion and said element for receiving complementary parts of yarn spool journals, said element when moved from its operative position providing an opening between it and 35 said body portion for the passage of said parts into and from said grooves, means to hold said element in its operative position, and a guide arm extending from said element and having a guiding surface 40 for guiding said parts into said opening.

14. A connecting member for the journals of adjacent ends of co-axial yarn spools of a tube frame, comprising a body having a cylindrical portion adapted to rotate in a bearing and having transverse grooves extending entirely across the respective end portions thereof and extending into said cylindrical portion for receiving complementary parts of yarn spool journals.

50 15. A connecting member for the journals of adjacent ends of co-axial yarn spools of a tube frame, comprising a cylindrical body adapted to rotate in a bearing and having transverse grooves in the respective end portions thereof for receiving complementary parts of yarn spool journals, said grooves crossing the axis of said body, and a groove in one end portion thereof being set at an angle with respect to a groove in the other 55 end portion thereof.

16. A connecting member for the journals of adjacent ends of co-axial yarn spools of a tube frame, comprising a cylindrical body adapted to rotate in a bearing and having 65 parallel flanges projecting from the respec-

tive end portions thereof and having transverse grooves in the respective end portions thereof extending between said flanges and into the body portion inwardly of the flanges for receiving complementary parts of yarn 70 spool journals.

17. A connecting member for the journals of adjacent ends of co-axial yarn spools of a tube frame, comprising a cylindrical body adapted to rotate in a bearing and having parallel flanges projecting from the respective end portions thereof and having transverse grooves in the respective end portions thereof extending between said flanges and into the body portion inwardly of the flanges 75 for receiving complementary parts of yarn spool journals, said grooves crossing the axis of said body, and a groove in one end portion thereof being set at an angle with respect to a groove in the other end portion thereof. 80

In testimony whereof we affix our signatures.
